UNITED STATES PATENT OFFICE

FREDERICK J. CLARK, OF BUFFALO, NEW YORK, ASSIGNOR TO STEAM PRESSING IRON COMPANY, OF CHICAGO, ILLINOIS

PRESSING IRON

Application filed June 15, 1927. Serial No. 198,942.

This invention relates to pressing irons and the like, and particularly to the fluid control valves which are frequently provided on such irons. It is also in the nature 5 of an improvement upon the type of pressing iron or the like disclosed and claimed in my prior copending application Serial No. 95,262, filed March 17, 1926.

An object of this invention is to generally 10 improve and simplify pressing irons and the like having fluid control valves.

A further object of the invention is to provide an improved pressing iron or the like with which a more satisfactory and convenient 15 control of the fluid controlling valve may be obtained; with which the manipulation of the valve may be made more convenient, and also made adjustable for the greater convenience of different persons who 20 may use the iron; with which the danger of injury to cloth being ironed or pressed by improper operation of the valve is greatly reduced, and which will be exceptionally simple, durable, compact, convenient and 25 relatively inexpensive.

Various other objects and advantages will be apparent from the following description of an embodiment of the invention, and the novel features will be particularly pointed 30 out hereinafter in connection with the appended claims.

In the accompanying drawings:

Fig. 1 is a plan of a pressing iron constructed in accordance with this invention;

Fig. 2 is an end elevation of the same;

Fig. 3 is a plan of a portion of the same, with a part of the valve controlling mechanism in section;

Fig. 4 is a similar plan, but with the parts in a different operative position;

Fig. 5 is a sectional elevation of a portion of the iron, and showing the fluid conducting passages;

Fig. 6 is a sectional elevation of a portion of the iron, the section being taken approximately along the line 6-6 of Fig. 3;

Fig. 7 is a similar elevation, but taken as indicated along the line 7-7 of Fig. 4; and

Fig. 8 is a sectional elevation of a portion

of the same, with the section taken approximately along the line 8-8 of Fig. 1.

In the illustrated embodiment of the invention, the pressing iron may be of any suitable shape or size, and comprises a body 1 provided with a suitable handle 2 by which it may be manipulated. This iron may be heated in any desired manner, such as by electricity, gas or steam, but in the illustrated embodiment it is indicated as of the electrically heated type, having the usual socket guard 3 at its rear end for receiving the socket plug (not shown) of an electrical connection cable, as usual in electric pressing irons.

A fluid, such as steam or other source of moisture, may be conducted into the iron through a suitable fluid supply conduit (not shown) connected to a pipe 4 leading into the body of the iron from the upper surface thereof, as shown in Figs. 1 and 2. This pipe 4 leads into the interior of the body of the iron 1, and may be connected by internal conduits 5 and 6 with a valve casing 7 which may be secured to the upper face of the body of the iron 1 in any suitable manner, such as by screws 8. The valve casing 7 has a pair of conduits 9 and 10 therein opening through the lower face thereof in spaced relation to one another, and also opening into a valve passage 11, Figs. 3 and 4, on opposite sides of a valve seat 12 of that passage. One of said conduits, such as the conduit 9, communicates with the conduit 6 of the iron body, and the conduit 10 of the valve casing may communicate with a passage or conduit 13 in the iron body. The passage 13 in turn communicates with a distributing chamber 14 provided in the lower part of the iron body near and closely adjacent to the pressing surface 15 of that body, as usual in this type of pressing iron.

The valve casing 7 has a cylindrical or tubular extension 16 projecting therefrom endwise of the iron, and at its free end this extension is provided with a stuffing box 17 through which extends, and in which is guided, a valve stem or operating element 18. This valve stem reciprocates through the stuffing box, and in the passage 11. The

stem, at its inner end, terminates in a conical valve point 19 which is adapted to seat itself in the valve seat 12 and close the passage 11 whenever the stem is forced inwardly. 5 Thus the valve stem, by its position with respect to the valve seat 12, will control the discharge of fluid from the supply pipe 4 to the distributing chamber 14 in the bottom of the iron body. The distributing chamber 14 10 opens through the lower face of the pressing iron by means of a plurality of spaced apart, small passages 20, as usual in such irons.

One arm 21 of a U-shaped bracket 22 is rotatably fitted over the cylindrical, projecting extension 16 of the valve casing. 15 This arm 21 is slit from its aperture 23 outwardly, and the opposite sides of the slit are connected by a clamping screw 24, so that this arm may be adjustably clamped 20 to the cylindrical extension of the valve casing by a tightening of the screw 24. The opposite arm of the bracket extends across the axis of the valve stem and is provided with an aperture 25 into which a bearing 25 bushing 26 may be threaded, as clearly shown in Fig. 3. A helical compression spring 27 may be confined on the valve stem 18 between an end of the bushing 26 and a collar 28 of the stem 18, so as to urge 30 or bias the valve stem yieldingly and inwardly into closed position on the valve seat 12.

A lever 29 is loosely and rotatably confined on the outer end of the valve stem 18 between an abutment or collar 30 threaded upon the outer end of the stem and the adjacent end face of the bushing 26, the aperture in the lever 29 through which the stem extends being somewhat larger than 40 the diameter of the stem so as to permit of a fluid regulating movement of the lever 29. Thus, when the lever 29 is rocked by the movement of its free end in a direction lengthwise of the iron, the lever will fulfil 45 crum at a point intermediate of its ends against the bushing 26, and at its free end will engage and cam outwardly the collar 30 of the stem and thus will cam the valve stem outwardly against the action of the 50 biasing spring 27. This action is illustrated in Figs. 3 and 4, the valve stem being shown as in closed position in Fig. 3 and being illustrated in Fig. 4 as having been shifted into the open position by the movement of the lever 29 just described.

An operating button 31 is provided on the lever 29 at its free end, and this button 31 is positioned adjacent one end of the handle 2 so as to be convenient for operation by a 55 digit of one's hand while that hand is grasping the handle and manipulating the iron. For example, with the button disposed at the forward end of the handle 2, as illustrated, the button 31 may be readily engaged by the thumb of one's hand which is

grasping the handle, and the button and lever operated to shift the valve stem without removing the hand from the handle 2. The bracket 22 may be angularly adjusted 70 around the cylindrical extension 16 of the valve casing, so as to place the button 31 adjacent the end of the handle 2 at the point which is most convenient for the person expected to operate the iron.

A plate 32 may be secured to the free end 75 of and form an angular arm or continuation of the side arm of the U-shaped bracket 22 through which the valve stem extends. The plate is provided with an aperture or guiding slot 33 through which the lever 29 extends, and in which it is guided. This notch or aperture 33 may be L-shaped as shown in Figs. 6 and 7, one arm or branch 80 of the L extending parallel with the axis of the stem 18, and the other arm of the L 85 extending in a direction transverse to the direction of movement of the valve stem 18. Thus the lever 29 will be first guided along the horizontal arm of the L slot as it is moved to shift the valve stem into open position, the branch of the L in which the lever 90 29 is then moving being of sufficient length to permit movement of the valve stem into open position before reaching the end of that branch of the slot.

When the lever 29 meets the end of the horizontal branch of the L slot 33, the valve 95 stem will be in open position and the lever will be in alinement with the other or transverse branch of the L-shaped aperture or slot 33, whereupon the lever 29 may be shifted laterally of the direction of its previous movement, that is, it may be rotated to a limited extent about the axis of the stem 18 so as to move into the offset or other 100 branch of the L-shaped slot 33. This carries the lever 29 behind a shoulder 34 of the slot, and this shoulder prevents movement of the lever 29 under the influence or urge of the spring 27. Thus the lever 29 105 will be releasably held in open position, and the valve stem will permit free flow of fluid to the distributing chamber 14. To release the controlling lever or element 29, it is merely necessary to first rotate it about the 110 axis of the stem 18 until it is disengaged from the shoulder 34, whereupon the spring 27 returns the valve stem to closed position and shifts the lever 29 back along the horizontal branch of the L-shaped slot 33, 115 provided the operator permits such movement by releasing the button 31 from the digit of the hand controlling it.

It will be noted that the lever 29 which 120 controls the valve stem acts as a controlling member and has movements in two directions independently of one another, in one of which directions it operates the valve between its closed and open positions, and in the other of which it effects the securing 125 130

of itself in, or the releasing of itself from, an adjusted position such as the open position. While for the purpose of simplicity, the guiding slot or aperture 33 has been shown as L-shaped, by which the lever may be secured in only one adjusted position, it will be obvious that the slot or aperture 33 may be provided with any number of offset or laterally extending branch notches leading from the horizontal branch and into which the lever or controlling member 29 may be displaced laterally in order that the lever, and through it the valve stem, may be secured releasably in a number of different adjusted positions, thus variably controlling the flow of fluid through the valve casing.

By being able to secure the valve in open or partially open position, there is little danger of an operator unintentionally and unknowingly partially or entirely releasing the button 31 and thus partially or entirely shutting off the valve while manipulating the iron, and therefore the danger of injury to the cloth by the absence of moisture is very greatly reduced.

The stem 18 is free to rotate about its own axis, except for the friction resistance offered by the spring 27 and other parts engaging the stem. If any particles of solid matter, such as dirt, should work into the valve passage 11 and interfere with the closing of the stem 18, such particles may be easily removed without dismantling the valve mechanism merely by rotating the stem about its own axis, or by tapping upon the outer end of the stem in a direction endwise of the stem, or by both tapping and rotating the stem.

To prevent wobbling of the stem 18 in the packing box, a guiding sleeve 18^a in which the stem 18 is rotatably and slidably fitted may be disposed in the valve passage 11 and confined therein against a shoulder of that passage by the packing of the box 17. The collar 30 may be releasably secured in adjusted positions by a lock nut 30^a threaded upon the outer end of the stem and a spring split washer 30^b disposed on the stem 18 between the collar 30 and the lock nut 30^a.

It will be noted that the valve controlling parts are all mounted on the valve casing, and the casing detachably secured on the body of the iron, which greatly simplifies the construction and facilitates the assembly of the iron. The casing and parts mounted thereon constitute a unit removably attachable to the iron. The extent of movement of the valve stem for any given movement of the controlling lever or member 29 may be varied to some extent by adjusting the collar 30 along the valve stem.

It will be understood that various changes in the details, which have been herein described and illustrated in order to explain the nature of the invention, may be made by

those skilled in the art within the principle and scope of the invention as expressed in the appended claims.

I claim:

1. In a pressing iron or the like provided with a handle, a fluid controlling valve having a valve stem, and means for operating said valve stem including a controlling member extending into a position for operation by a digit of one's hand while that hand is grasping said handle, means mounting said member for rocking movement in one path to cause movement of the valve stem, and also independently of that movement in a direction transversely to said path, said iron having a portion cooperating with said member when the latter is moved transversely to said path, while at a particular point of its movement in said path, for securing said member releasably at said point.

2. In a pressing iron or the like provided with a handle, a fluid controlling valve having a valve stem, means for operating said valve stem and including a controlling member extending into a position for operation by a digit of one's hand while that hand is grasping said handle, means mounting said member for movement in one path to cause operation of said valve stem, and also shiftable laterally of that path without causing operation of said valve stem, and a guide for said member having a notch in a side wall thereof into which said member by movement laterally of said path may be shifted to latch the member in a selected position into which it may be moved.

3. In a pressing iron or the like, provided with a handle, a fluid controlling valve having an operating element movable between open and closed positions and yieldingly biased into one of said positions, said element having an abutment, a lever engageable against said abutment and fulcrumed against said iron for operating said element against its bias into the other of said positions, means mounting said lever for independent movement along said abutment in a direction transverse to the movement it imparts to said element, and means cooperating with said lever when the latter has been shifted transversely after movement of said element into said other of said positions, for securing said lever in that position.

4. In a pressing iron or the like, provided with a handle, a fluid controlling valve having an operating element movable between open and closed positions and yieldingly biased into one of said positions, said element having an abutment, a lever engageable against said abutment and fulcrumed against said iron for operating said element against its bias into the other of said positions, means mounting said lever for independent movement along said abutment in a direction transverse to the movement

it imparts to said element, and an abutment on said iron behind which said lever may be engaged and releasably secured when shifted transversely after it has moved said element into said other of said positions, whereby said element may be releasably held in said other of said positions.

5. In a pressing iron or the like provided with a handle, a fluid controlling valve having an operating stem and resiliently biased in endwise direction into one fluid controlling position, a lever freely rotatable on said stem, means limiting endwise movement of said lever on said stem, a fulcrum upon which said lever may be rocked and lengthwise of which it may be moved while rotating on said stem to shift said stem endwise into another fluid controlling position, and securing means with which said lever may be engaged by its rotation on said stem to hold said lever in a selected position into which it may be moved against its bias while operating said stem.

6. In a pressing iron or the like provided with a handle, a fluid controlling valve having an operating stem and resiliently biased in endwise direction into one fluid controlling position, a lever rotatable on said stem, means limiting endwise movement of said lever on said stem, a fulcrum upon which said lever may be rocked and lengthwise of which it may move while rotating on said stem, to shift said stem endwise into another fluid controlling position, and an abutment behind which said lever may be latched by its rotation on said stem to secure said lever releasably in a selected position into which it may be moved against its bias while operating said stem.

7. In a pressing iron or the like provided with a handle, a fluid controlling valve having an operating stem and a casing with a cylindrical portion through which said stem passes, a bracket guiding said stem between open and closed positions, and having a split ring portion fitting said cylindrical portion, means for drawing together the sections of said ring on opposite sides of the slit to clamp said bracket to said portion, and permitting adjustment of said bracket rotatably about said cylindrical portion, and means connected to said stem and guided by said bracket for operating the stem in one direction between said positions, said means extending into a position for operation by a digit of one's hand while that hand is grasping said handle, the adjustment of the bracket permitting adjustment of said means into the position for operation most convenient for any person.

8. In a pressing iron or the like provided with a handle, a fluid controlling valve having an operating stem, a bracket having an aperture through which said stem extends for guiding said stem in a direction end-

wise of itself, a spring acting between said bracket and the stem for biasing said stem into closed position, said stem having a collar, a lever loosely and rotatably mounted at one end on said stem between and bearing against said collar and said bracket, whereby the lever may fulcrum against the bracket and when rocked on that fulcrum will by engaging the collar, shift the stem endwise against the action of the spring, and means cooperating with said lever when said lever is rotated upon said stem for securing the latter and through it the valve in open position.

9. In a pressing iron or the like provided with a handle, a fluid controlling valve having an operating stem, a bracket having an aperture through which said stem extends for guiding said stem, a spring acting between said bracket and the stem for biasing said stem into closed position, said stem having a collar, a lever loosely and rotatably mounted at one end on said stem between and bearing against said collar and said bracket, whereby the lever may fulcrum against the bracket and when rocked on that fulcrum will by engaging the collar, shift the stem endwise to open the valve against the action of the spring, and a guide carried by said bracket and having means cooperating with said lever for guiding said lever first in a direction to move the stem in an opening direction and then permitting a limited rotation of said lever about the axis of the stem, the guide and lever cooperating when the latter is rotatably displaced to secure the lever and through it said stem in open position.

10. In a pressing iron or the like provided with a handle, a fluid controlling valve having an operating stem, a bracket having an aperture through which said stem extends for guiding said stem, a spring acting between said bracket and the stem for biasing said stem into closed position, said stem having a collar, and a lever loosely and rotatably mounted on said stem between and bearing against said collar and said bracket, said bracket having a slot through which said lever passes, said slot being angular with one arm of the L extending approximately parallel to the axis of the stem, whereby said lever will be first guided by one arm of the slot in a direction to cam the stem into open position until the lever reaches the other arm of the slot, the lever then being rotatable about the axis of the stem into said other arm of the slot to secure the lever releasably in a position in which the valve is held open.

11. In a pressing iron or the like provided with a handle, a fluid controlling valve carried by said iron and having a projecting cylindrical portion and an operating stem extending outwardly through the cylindri-

cal portion, a bracket having a slit apertured end adjustably clamped on the cylindrical portion of said valve for rotatable adjustment about the same, the free end of said bracket extending across the axis of the stem and having an aperture for receiving and guiding said stem between open and closed positions, a collar on the outer end of said stem, a lever loosely mounted 10 at one end on said stem between and bearing against said collar and bracket, and a spring acting between said bracket and stem for biasing said stem into closed position, the free end of said lever extending into a 15 position for operation by a digit of one's hand while that hand is grasping the handle, whereby the free end of said lever may be fulcrumed against the bracket to cam the collar and stem outwardly into open 20 position against the action of said spring.

12. In a pressing iron or the like, a valve casing removably secured to the body of the iron and having a fluid passage communicating with the interior of the iron body, 25 a valve element extending into said casing and controlling said passage, a bracket extending from said casing and having a bearing for mounting and guiding said element, an operating member for said element connected thereto for moving it between open 30 and closed positions, said bracket having means to latch said member releasable in one of its positions against movement towards the other position, and said member, 35 said valve element, said casing and said bracket being connected together to form a unitary device attachable to and detachable from the iron body.
